UNITED STATES PATENT OFFICE.

ARTHUR T. KUEHNER, OF ST. AUGUSTINE, FLORIDA.

JOURNAL BOX.

Original application filed January 18, 1921, Serial No. 478,646. Divided and this application filed July 20, 1922, Serial No. 576,343. Renewed September 10, 1925.

This invention relates to an improved journal box for locomotives, being a division of my co-pending application for journal box, filed January 18, 1921, Serial No. 478, 646, now Patent No. 1,547,657, granted on July 28, 1925.

The invention seeks, as one of its principal objects, to provide a journal box employing a shelf between the legs thereof for supporting a grease cellar while acting to rigidly brace the legs with respect to each other and wherein the cellar may be readily removed without the necessity for displacing the shelf.

15 The invention has as a further object to provide a journal box wherein the cellar will be provided with an opening in the bottom wall thereof to accommodate a spring bearing between the shelf and a follower within 20 the cellar and wherein the shelf will be provided with means for directing said spring onto the shelf when the cellar is shifted to 25 position between the box legs.

A still further object of the invention is 30 to provide a journal box wherein the shelf and the cellar will be formed with mating lugs whereby the cellar may be secured in position.

35 And the invention has as a still further object to provide a journal box wherein the shelf and cellar will be formed with coacting means for limiting the cellar in its inward movement between the box legs.

Other and incidental objects will appear 40 hereinafter.

In the drawings:

Figure 1 is a front elevation showing a journal box embodying the present invention,

45 Figure 2 is a vertical sectional view taken medially through the box,

Figure 3 is a fragmentary rear elevation of the box body, the cellar being removed, and

50 Figure 4 is a perspective view of the shelf employed.

Referring now more particularly to the drawings, I have shown the present invention in connection with a journal box of the character illustrated in the parent application previously identified. This box includes a box body 10 in which is mounted a crown brass 11 for journaling a drive axle, as conventionally illustrated at 12, and

55 formed on the legs of the box body at the inner side thereof are depending lugs 13 while at the outer side of the box body said legs are provided with lugs 14. At its upper end, the box body is provided with spring saddle recesses 15 and 16, in the former of which is seated a liner 17 while, as shown in Figure 2, the latter recess opens through the outer side of the box body. Removably seated against the outer side of the box body is a face plate 18 fitting the crown brass and 60 provided at its lower ends with lugs 19 mating with the lugs 14 of the box body. As shown in Figure 1, the face plate overhangs the box body to provide pedestal flanges 20 to cooperate with similar pedestal flanges 21 65 at the inner end of the box body and, as will be observed, the face plate is formed of companion sections at the upper ends of which are lugs 22 through which is engaged a bolt 23 connecting the upper ends of the 70 sections. Extending from the sections of the plate are lugs 24 lying within the recess 16 to provide a liner for said recess similar to the liner 17, the recesses 15 and 16 being adapted to receive the legs of a spring 75 saddle as conventionally illustrated at 25. Thus, the weight of the load upon the spring saddle will hold the face plate against upward movement. All of the structure so far described forms a part of the subject matter 80 of my parent case and further description of such structure in the present case is accordingly believed unnecessary.

Coming now more particularly to the subject of the present improvements, I employ 85 a shelf 26 which fits snugly between the legs of the box body to abut shoulders 27 on said legs and depending from the shelf are pairs of lugs 28 and 29 mating with the lugs 13 and 14 respectively of the box body. Extending through the lugs 13 and 28 is a tie bolt 30 and extending through the lugs 14 and 29, as well as through the lugs 19 of the face plate 18, is a tie bolt 31. Formed in the inner end margin of the shelf medially thereof, is, as particularly shown in Figure 4, an inclined guideway 32 and extending from the rear end edge of the shelf are spaced ears 33.

100 Removably fitting between the legs of the box body, upon the shelf 26, is a grease cellar 34, the side walls of which are provided at their lower margins with ribs 35 coacting

with the shoulders 27 of the box legs while upon the upper margins of said side walls are formed similar ribs 36 coacting with shoulders 37 upon the inner sides of the 5 box legs. These ribs and shoulders will serve to space the side walls of the cellar from the legs of the box body so that any tendency toward sticking of the cellar will be minimized. At its outer end, the cellar 10 is provided with spaced ears 38 mating with the ears 33 of the shelf and extending through said ears are bolts 39 locking the cellar in position. The bottom wall of the 15 cellar is provided with a medial opening 40 therethrough and freely mounted within the cellar is a follower 41, to which is connected at one end a coil spring 42, freely received through said opening to coact with the shelf so that the spring will thus operate to 20 urge the follower upwardly within the cellar for pressing a grease cake within the cellar against the journal of the axle.

It is now to be observed that the cellar 25 may, by simply removing the bolts 39, be withdrawn from between the legs of the box body and may thus be removed without either lifting or lowering the cellar or molesting the shelf 26. The shelf, being positioned between the legs of the box body, will 30 rigidly space the legs apart while the tie bolts 30 and 31 will rigidly hold the legs against spreading movement. Thus, cramping of the cellar by the box legs will be prevented so that the cellar may be easily re- 35 charged and, in this connection, the purpose of the inclined guideway 32 becomes apparent. As will be seen, after the cellar has been removed and a grease cake is arranged therein, the spring 42 will project through 40 the opening 40 in the bottom wall of the cellar therebeneath. Accordingly, when replacing the cellar, it becomes necessary, before the cellar can be slidably shifted into 45 place upon the shelf, to guide the lower end of the spring onto the shelf. This is done by engaging the lower end of the spring, after the cellar has been advanced sufficiently, with the guideway 32, when the cellar may then be further shifted into position, the guideway serving to ride the lower 50 end of the spring up onto the shelf. At the inner ends of the ears 33, the shelf is provided with shoulders 43 while at the inner ends of the ears 38 of the cellar are formed 55 shoulders 44 to coact, as shown in Figure 2, with the shoulders 43 for limiting the cellar in its movement between the legs of the box body to the left in Fig. 2. Thus, the cellar cannot accidentally shift outwardly of the 60 truck to bear against a wheel hub, when applied to a locomotive truck, in which case the cellar is inserted from the inner side of the journal box.

Having thus described the invention, what is claimed as new is:

65

1. A journal box including a box body having legs, a shelf secured between said legs, a cellar supported by said shelf, a follower disposed within the cellar, and yieldable means extending through the bottom wall 70 of the cellar to project therebeneath and coacting between the follower and the shelf, the cellar being insertable between the legs by sliding the cellar inwardly upon the shelf and the shelf being provided with means to 75 coact with the lower end of said yieldable means for directing said yieldable means onto the shelf when the cellar is shifted inwardly.

80

2. A journal box including a box body having legs, a shelf secured between said legs, a cellar supported by said shelf, a follower disposed within the cellar, and yieldable means extending through the bottom wall of the cellar to project therebeneath 85 and coacting between the follower and the shelf, the cellar being insertable between the legs by sliding the cellar inwardly upon the shelf and the shelf being provided with an inclined guideway for directing said yield- 90 able means onto the shelf when the cellar is shifted inwardly.

85

3. A journal box including a box body having legs, a shelf secured between said legs, a cellar shiftable inwardly between the 95 legs to a position resting upon said shelf, the cellar and shelf being provided with mating ears and being formed at the inner ends of said ears with shoulders coacting for limiting the shelf in its inward movement, 100 and fastening means extending through said ears securing the cellar in position.

100

4. A journal box including a box body having legs, a shelf secured between said legs, a cellar shiftable inwardly between the 105 legs to a position resting upon said shelf, the cellar and shelf being provided with stops co-acting for limiting the shelf in its inward movement, means spacing the cellar from the legs whereby the cellar may be 110 freely removed, and means for securing the cellar in position.

105

5. In a journal box, the combination of a box body having legs, a shelf secured between said legs rigidly spacing the legs 115 apart, a cellar mounted upon the shelf to contain and hold grease independently of the shelf, the cellar and shelf being provided with mating ears, fastening means coacting with said ears securing the cellar in position, and means spacing the cellar from the legs whereby the cellar may be freely re- 120 moved.

115

In testimony whereof I affix my signature.

ARTHUR T. KUEHNER: [L.S.]
